UNITED STATES PATENT OFFICE.

ROBERT MOY, OF MODENA, WISCONSIN.

STRAW-STACKER.

SPECIFICATION forming part of Letters Patent No. 601,667, dated April 5, 1898.

Application filed September 2, 1897. Serial No. 650,365. (No model.)

To all whom it may concern:

Be it known that I, ROBERT MOY, a citizen of the United States, residing at Modena, in the county of Buffalo and State of Wisconsin, have invented a new and useful Straw-Stacker, of which the following is a specification.

My invention relates to improvements in straw-stackers of that class wherein the stacker may be swung automatically from side to side of the threshing-machine; and the primary object of the invention is to provide an improved stacker mechanism which is applied permanently to the threshing-machine to form an integral part of the same.

A further object of the invention is to provide a novel supporting and actuating mechanism for the swinging stacker in which the parts are sustained in a peculiar manner to obviate the weight of the stacker mechanism binding or cramping the driving devices of the stacker.

A further object of the invention is to construct the swinging part of the stacker mechanism in a manner to enable the same to be folded over and upon the threshing-machine without allowing any of the elements of the stacker mechanism to rest upon the ground.

With these ends in view and with such others as will appear from the annexed detailed description my invention consists in the novel combination of elements and in the construction and arrangement of parts, which will be hereinafter fully described and claimed.

To enable others to understand my invention, I have illustrated the preferred embodiment thereof in the accompanying drawings, forming a part of this specification, and in which—

Figure 1 is a plan view of my improved straw-stacker applied to a part of a threshing-machine, a part only of the thresher being shown for the purpose of illustrating the application of the stacker thereto. Fig. 2 is a vertical longitudinal sectional elevation on the plane indicated by the dotted line 2 2 of Fig. 1. Fig. 3 is a horizontal sectional view on the plane indicated by the dotted line 3 3 of Fig. 2, showing the driving and reversing gearing. Fig. 4 is a vertical transverse sectional view on the plane indicated by the dotted line 4 4 of Fig. 3 to show the mechanism

for turning the swinging stacker-frame. Fig. 5 is a detail transverse sectional view to show the reversing mechanism for the stacker-adjusting shaft to impart the swinging motion to the swinging frame and the stacker carried thereby. Fig. 6 is a detail sectional view on the plane indicated by the dotted line 6 6 of Fig. 3.

Like numerals of reference denote corresponding and like parts in each of the several figures of the drawings.

A part of the main frame or casing of an ordinary threshing-machine of any suitable or preferred construction is indicated by the numeral 1 in the drawings.

No novelty is claimed herein for the threshing-machine, because my invention is restricted to the stacker mechanism.

I contemplate the provision of a stacker which shall be applied permanently to a thresher-machine and form an integral part of the same, and as a means for attaching the stacker to the threshing-machine I provide the main supporting-frame 2, which has its side sills 3 extended into the machine casing or frame 1 to be bolted or otherwise united solidly to the casing or frame 1. This supporting-frame extends rearwardly beyond the main frame for a suitable distance, and the side sills of said frame 2 are braced by the transverse bars 4 and the diagonal bars 5, all of said parts being bolted solidly together. Above this main supporting-frame 2 is arranged the swinging stacker-carrying frame 6, which occupies a parallel relation to the main supporting-frame 2. This swinging frame 6 and the supporting-frame 2 are coupled or united together by a vertical king-bolt or arbor 7, which passes through the diagonal bars 6^a of the swinging frame and the diagonal bars 5 of the main frame 2. On the lower face or side of this swinging frame 6 is applied and bolted a circular metallic track 8, and on the upper side of the supporting-frame 2 is secured the brackets 9 of a series of antifriction supporting-rollers 10, upon which ride the circular track 8 of the swinging stacker-frame 6, whereby the swinging frame is adapted to turn freely in a horizontal plane on the king-bolt or arbor and the supporting-rollers. The weight of the swinging frame and the stacker is borne practically

cally by the antifriction-rollers on the main supporting-frame, and by this construction the weight of the stacker is prevented from binding or cramping the gearing of the driving mechanism, thereby permitting the driving mechanism to turn freely with minimum friction and wear on the parts. This swinging frame is provided on its upper side with the cross-rails 11, which are suitably bolted 5 to the frame and are spaced apart a suitable distance from each other. These cross-rails carry the brackets 12, which are bolted to the ends of said rails, and in the brackets is journaled a shaft 13, which forms the pivot-shaft 10 for the foldable stacker and as a driving-shaft for the endless conveyer-belt of said stacker. From the brackets 12 of the swinging frame extend the arms 14, and from the rear cross-rail 11 on said frame extends another pair of arms 15. These two pair of arms 14 15 sustain an inclined board 16, the transverse shaft 17, and the idler-rollers 18, and around this board the rollers 19 on the shaft 17 and the idler-rolls 18 passes a traveling auxiliary conveyer 20, which is arranged below an upper inclined conveyer 21, so as to catch any straw which may escape from the conveyer 21 and to serve as a means for depositing the escaping straw upon the 25 stacker-conveyer. The shaft 18 of the auxiliary conveyer 20 is provided with a chain-wheel 22, around which passes a sprocket-chain 23, which also passes around a sprocket-wheel 24 on one end of the shaft 13, thus 30 gearing the shafts 13 18 together for driving the conveyer 20.

The conveyer 21 is carried by a frame 25, which is pivotally or loosely attached to a shaft 26, which is journaled in suitable bearings 27, attached to the threshing-machine 40 adjacent to the sieves or riddles thereof. This shaft 26 is provided at its end with a driving wheel or sprocket 28, and on the shaft is mounted the conveyer-pulleys 29, around 45 which pass the conveyer-belt 21, the other part of the belt or apron 21 passing around idler-rollers 29^a, suitably journaled at the free end of the adjustable frame 25. This conveyer 21 and its adjustable frame are arranged to occupy an inclined position between the sieves or riddles of the threshing-machine and the stacker-conveyer, and the free rear end of said conveyer 21 is designed to overhang the stacker-conveyer in order that the 50 conveyer may properly deposit the straw from the threshing-machine upon the stacker-conveyer. This frame 25 and the conveyer are adapted to be adjusted to different inclinations with relation to the stacker-conveyer 55 as the latter may be raised or lowered, and as a means for effecting this adjustment of the inclined conveyer and its frame I have provided the shaft 31, which is journaled in suitable bearings on the machine frame or 60 casing 1. This shaft is provided at one end with a suitable crank 31^a for its convenient rotation by hand, and between the shaft 31

and the inclined conveyer-frame are arranged the suspending and adjusting ropes 32, each rope being attached to the conveyer-frame 25 70 and wound upon the shaft 31, whereby the ropes serve to suspend the free end of the inclined conveyer-frame, and the shaft and ropes enable the attendant to adjust the conveyer 21 as may be required. 75

The stacker-frame is made in sections, (indicated at 32^a 33), although any suitable number of sections may be used to form the complete stacker-frame. The sections of the stacker-frame are hinged together at 34 to enable the sections to abut against one another when the stacker is extended to bring its members into alinement with each other and to enable the outer member 33 to fold upward with relation to the lower member 32^a in order that the outer member may fold over and upon the threshing-machine 1. The inner or lower member 32^a of the stacker-frame is loosely or pivotally mounted on the shaft 13, and this pivotal connection of the lower member 32^a of the stacker-frame is effected, preferably, by providing the said member 32^a with forked arms or plates 35, which are rigidly fastened to the member 32^a and which loosely embrace the shaft 13. The sectional stacker-frame thus has its lower member pivoted on the shaft 13, which is carried by the swinging frame 6, and the two members of the stacker-frame are also pivoted together to enable one member to be turned upward with 85 relation to the other member. The stacker-frame thus has its members mounted for adjustment in a vertical direction, as well as to fold upon the thresher, and at the same time the stacker-frame is mounted on the swinging frame 6 to swing therewith in a horizontal plane, thus giving to the stacker-frame the desired lateral motion with respect to the threshing-machine. This stacker-frame carries at its outer end the idler-rollers 36, and around the rollers 37 on the shaft 13 and the idler-rollers 36 passes the endless conveyer 38 of the stacker, which conveyer is thus carried by the stacker-frame in a position to receive from the conveyer 21 and to deliver 90 the straw out over the free end of the inclined stacker. The stacker is sustained in its proper position by means of the cables 39, which are attached to the outer member 33 of the stacker-frame, and these cables 39 are carried through 95 an eye 40 on the guide-bail 41, which is mounted pivotally upon the top of the threshing-machine, the ends of the cables being coiled or wrapped on an adjusting-shaft 42, which is journaled on the machine 1 and provided 100 with a hand-crank 43 and with a pawl-and-ratchet locking device 44.

The guide-bail 41 is erected above the machine 1 to give clearance of the stacker-suspending cables, and the weight of the stacker and the strain of its suspending-cables tends to force the pivoted guide-bail outward and rearward toward the stacker. To overcome 110 this strain and to provide for holding the

guide-bail in its raised position, I provide the holding-cable 45, which is fastened at one end to the guide-bail and which has its other end coiled on the shaft 46, suitably journaled on the top of the machine 1, and said shaft is provided with a hand-crank 47 and with a pawl-and-ratchet locking device 48. The described construction of the cables and shafts provides for the proper raising or lowering of the sectional stacker to sustain the same in its operative position and to enable the same to be folded, and said devices also hold the guide-bail in position and enable the same to be folded upon the main machine when the stacker is folded thereon. The suspending-cables for the stacker have branch cables 49, which extend to and are coiled on the protruding end of the adjusting-shaft 50, which is journaled on the bottom side of the stacker-section 32^a, said shaft 50 having a suitable locking device and operating-crank. The outer stacker-section 33 is further provided with a pair of rigid arms 51, to which are attached the auxiliary cables 52, which are coiled on a shaft 53, journaled on the lower side of the stacker-section 32^a and provided with a suitable crank and a locking device.

On the vertical king-bolt or arbor is mounted a double master-gear 55, which is arranged between the main supporting-frame 2 and the swinging frame 6, and this master-gear is provided with teeth on both its upper and lower surfaces.

In the main supporting-frame 2 is journaled a driving-shaft 56, one end of which has a pulley or chain-wheel 57, around which passes a belt or sprocket-chain to drive the shaft 56, and the inner end of this shaft carries a bevel gear-pinion 58, which meshes with a series of bevel gear-teeth on the lower face of the master-gear 55 for the purpose of driving the latter. On the swinging frame 6 is journaled a counter-shaft 59, the inner end of which has a gear-pinion 60, that meshes with the gear-teeth on the upper face of the master-gear 55, and the outer end of this counter-shaft 59 has a sprocket-wheel 61, around which passes a sprocket-chain 62, that passes around a sprocket-wheel 63 on one end of the shaft 13, that drives the conveyer belt or apron of the stacker. The described construction and arrangement of shafting and gearing provide for the transmission of power from a suitable shaft to the stacker-conveyer without in any way interfering with the horizontal turning movement of the frame 6 to swing the stacker in laterally-inclined relation to either side of the main machine 1. The driving-shaft 56 also carries a double pulley 64 65, around which pass the straight and crossed belts or chains 67 68, and these straight and crossed chains pass around other sprocket-wheels 69 70, respectively, on an intermediate shaft 71, one sprocket-wheel and its chain serving to drive the intermediate shaft 71 in one direction, while the other sprocket-wheel and chain serve to drive the shaft 71 in the other direc-

tion. The sprocket-wheels 69 70 are mounted loosely on the shaft 71, and said wheels are designed to be made fast alternately therewith by a shiftable clutch 72, which is keyed and slidably mounted on the shaft 71 to rotate therewith and to play back and forth between the wheels 69 70.

To the clutch 72 is connected a fork 73 on the shipper bar or rod 74, which is slidably confined in suitable keepers attached to the front cross-bar of the main supporting-frame 2, and a trip arm or lever 75 is slidably connected to this shipper arm or lever. This trip-lever is fulcrumed on the main supporting-frame 2, and it is held normally in position by means of a spring 76. This trip-lever 75 lies in the path of the detents 77, which are attached to the front side of the swinging frame 6, near the ends thereof, and as the frame 6 swings back and forth to move the stacker-frame and its conveyer laterally these detents strike the trip-lever alternately to shift the clutch back and forth on the shaft 71 into engagement with the pulleys or sprocket-wheels 69 70 alternately. The swinging frame is turned on the king-bolt or arbor to give the laterally-swinging motion to the stacker by means of the cable or cables 78 79, which are attached to the respective sides or ends of the swinging frame 6 and which are coiled in reverse directions on the actuating-shaft 80, one cable being arranged to wind on the shaft 80 as the other cable is unwound therefrom. This shaft 80 is journaled in the frame 2 at a suitable distance from the shaft 71, and the two shafts 71 80 are geared together through the short shaft 81, journaled in suitable bearings on the frame 2 and having bevel-gears 105 which intermesh with similar bevel-gears on the shafts 71 80, as clearly shown by the drawings.

As the shaft 80 is driven in one direction by one of the pulleys 69 or 70, the shaft 71, and the short shaft 81 it winds one cable thereon and slackens the other cable to swing the frame 6 and the stacker in one direction. When the frame 6 has reached the limit of its movement in one direction, a detent strikes the trip-lever to shift the shipper-rod and move the clutch in engagement with the other pulley or wheel, thus driving the shaft 71 in the opposite direction, and this reverse motion of the shaft 71 is communicated through the short shaft 81 to the shaft 80, which is thus reversed to wind the other cable thereon to pull the frame 6 in the reverse direction and give an opposite motion to the stacker until the other detent on the frame 6 strikes the trip-lever, whereupon the motion of the frame 6 is again reversed. At the same time the master-gear transmits the motion from the shaft 59 to the shaft 13 and the latter drives the stacker-conveyer and the auxiliary conveyer 20. The conveyer 21 is driven by a suitable belt or chain which passes around a pulley or sprocket-wheel on the shaft 26.

It is thought that the operation of my in-

vention will be readily understood from the foregoing description, taken in connection with the drawings.

I am aware that changes in the form and proportion of parts and in the details of construction of the devices herein shown and described as the preferred embodiment of my invention may be made by a skilled mechanic without departing from the spirit or sacrificing the advantages of my invention. I therefore reserve the right to make such modifications and alterations as fairly fall within the scope of the invention.

Having thus fully described my invention, what I claim as new, and desire to secure by Letters Patent, is—

1. In a straw-stacker, the combination with a swinging frame, and a power-shaft, of an actuating-shaft, an intermediate shaft between the power and actuating shafts, clutch mechanism and connections between said power and intermediate shafts to drive the latter shaft in reverse directions alternately from the power-shaft, a yieldable trip operatively connected with said clutch, detents on the swinging frame to contact alternately with said yieldable trip, and connections between the actuating-shaft, the intermediate shaft and the swinging frame, substantially as described.

2. In a straw-stacker, the combination with a base-frame, a swinging frame pivoted on a fixed king-bolt or arbor and carrying a conveyer driving-shaft, and a double master-gear mounted loosely on said arbor and operatively connected with the conveyer driving-shaft, of a power-shaft geared to said master-gear and provided with two pulleys, an intermediate shaft having loose pulleys operatively connected by belts with said pulleys of the power-shaft, a clutch between the loose pulleys of the intermediate shaft, a spring-controlled trip mounted in the path of the swinging frame, means connecting said clutch and trip, and an actuating-shaft operatively connected with the intermediate shaft and said swinging frame, substantially as described.

3. The combination with a swinging stacker-carrying frame, and a supporting-frame, of an actuating-shaft, cables coiled reversely on the actuating-shaft and attached to the swinging frame, a power-shaft, an intermediate shaft geared to the actuating-shaft, the pulleys mounted on the intermediate shaft, belts fitted to said power-shaft and the pulleys to drive the latter in opposite directions, a clutch mechanism to make the pulleys fast with the intermediate shaft alternately, and a trip mechanism actuated by the swinging frame to control the clutch mechanism, substantially as described.

4. The combination with a swinging stacker-carrying frame, a power-shaft, and an actuating-shaft connected with said frame, of an intermediate shaft, the pulleys mounted on said intermediate shaft, the straight and crossed belts between the power-shaft and said pulleys, the clutch between said pulleys, the spring-trip connected with said clutch, and the spaced detents carried by the swinging frame and arranged to alternately strike the trip, substantially as described.

5. The combination with a swinging stacker-carrying frame, and a power-shaft, of an actuating-shaft, cables attached to the swinging frame and coiled in reverse directions on the actuating-shaft, an intermediate shaft geared to the actuating-shaft, pulleys mounted loosely on the intermediate shaft and geared to the power-shaft to be driven thereby in opposite directions, a slideable clutch between said pulleys, a shipper-rod, a trip connected to the shipper-rod, and detents carried by the swinging frame and arranged to alternately strike the trip, as and for the purposes described.

6. The combination with a main supporting-frame, a swinging stacker-carrying frame pivotally attached to the supporting-frame, and a stacker-conveyer driven by a shaft, 13, on said stacker-frame, of a power-shaft, a counter-shaft geared to the shaft, 13, a master-gear loose on the pivotal connection of the swinging frame and geared with the power-shaft and the shaft 13, an actuating-shaft having flexible connections with the swinging frame, an intermediate shaft geared to the actuating-shaft, a shifting mechanism including a clutch and operatively connecting the intermediate shaft with the power-shaft, and a trip-controlled tripper actuated by the swinging frame and connected with the clutch, for the purposes described substantially as set forth.

7. The combination with a swinging frame, and a sectional foldable stacker mounted thereon, of a stacker-adjusting shaft having cables which are branched and attached to the sections of the stacker-frame, a guide-bail through which the stacker-cables are passed, an adjusting-shaft having a flexible cable connected with the guide-bail, and an adjusting-shaft carried by one section of the stacker-frame and having cables connected with the other section of said stacker-frame, as and for the purposes described.

In testimony that I claim the foregoing as my own I have hereto affixed my signature in the presence of two witnesses.

ROBERT MOY.
